UNITED STATES PATENT OFFICE

2,134,458

CURTAIN

Bernadette M. Talbot, Manchester, N. H.

Application June 27, 1935, Serial No. 28,756
Renewed January 13, 1938

4 Claims. (Cl. 156—10)

My invention relates to an improvement in curtains, and particularly to an attachment to lace curtains and the like whereby the latter may be suspended from a curtain rod.

At the present time various means are employed to attach a curtain to a rod. The most common means is to fold the top of the curtain down upon itself a short distance, and fasten this folded end to the body of the curtain to form a sleeve for the reception of the rod. In practice, when the rod is being threaded through the sleeve, the end of the rod has a tendency to engage the threads of the curtain, and thereby tear the curtain.

In overcoming the above objections, I attain the principal object of my invention whereby I provide means to greatly diminish the likelihood of tearing a curtain when a rod is attached thereto.

Another object of my invention is to provide means for attaching a curtain to a rod whereby the rod is not visible from the inside of the curtain.

A further object of my invention is to provide means for facilitating the adjustment of the length of the curtain.

Other objects of my invention will be apparent from the following description of the present preferred form thereof, taken in connection with the accompanying drawings, wherein:

Figure 1 is a fragmentary view of a curtain having my improved curtain rod attaching means.

Figure 2 is a fragmentary view of my improved curtain, having the curtain rod attached thereto.

Figure 3 is a fragmentary view of my improved curtain, having the curtain rod attached thereto, the curtain being shown in adjusted position relative to Figure 1.

Figure 4 is a cross-sectional view of the curtain and rod, taken on line 4—4 of Figure 3, and looking in the direction of the arrow.

Figure 5 is a view similar to Fig. 3, the curtain being in adjusted position relative to Figures 1 and 3;

Figure 6 is a cross sectional view of the curtain and rod, taken on line 6—6 of Figure 5, and looking in the direction of the arrow.

In the drawings, wherein for the purpose of illustration is shown a preferred embodiment of my invention, 7 designates a curtain made of lace or similar material. The upper portion of this curtain is provided with retaining means for the curtain rod 8 by integrally forming with the curtain, loops 9, 10 and 11. These loops are

formed on the inside or wrong side of the curtain by interweaving them with the curtain, and are arranged in a series of rows to permit the rod to engage the proper row or rows to adjust the length of the curtain. These rows of loops are in alignment with each other, the purpose of which will be hereinafter explained.

Between the top of the curtain 7 and the uppermost row of loops 9 there is formed in the curtain a row of slots 12, which are in alignment with the loops 9, 10 and 11. These loops are adapted to pass through the slots 12 when the upper portion of the curtain is folded upon itself, as is clearly shown in Figures 2, 4, and 6 of the drawings. By this construction the folded portion 7a of the curtain 7 prevents the rod 8 from being visible from the outside of the curtain, as shown in Figure 2, and shields that portion of the curtain 7b immediately above the fold, from the rod 8. Moreover, by this construction the top of the curtain is given a finished heading.

In operation, the curtain 7 is so folded upon itself as to permit the loops 9 to be passed through the slots 12. When the curtain rod 8 is then threaded through the loops 9, the folded portion 7a of the curtain prevents the rod from being visible from the outside of the curtain, and shields the portion 7b from the rod. When the length of the curtain is to be shortened, the curtain is folded upon itself to permit the loops 9 to be passed through the slots 12, and the rod 8 is threaded through loops 9 and 10 by threading it through the first loop of the series of loops 9, then through the first loop of the series of loops 10, then through the second loop of the series of loops 10, and then through the second loop of the series of loops 9, and so on until the rod has been attached to the curtain (Figures 3 and 4). When further adjustment in the length of the curtain is to be made, the loops 9 are passed through the slots 12, and the rod 8 is threaded through loops 9, 10 and 11. These loops are brought together by so folding the curtain as to position loops 9 and 11 opposite each other, and by plaiting that portion 7c of the curtain to allow the loops 10 to be positioned between loops 9 and 11, thereby limiting the movement of the curtain 7 and the folded portion 7b away from the rod 8 (Figures 5 and 6).

It is to be understood that the form of my invention herein shown and described is to be taken as a preferred embodiment of the same, and the various changes in the shape, size and arrangement of parts may be made, without de-

50

55

parting from the spirit of my invention, or the scope of the appended claims.

What is claimed is:

- 5 1. A device of the character described comprising a curtain to be suspended on a rod, loops secured to the inner side of the curtain, said curtain having near its top a series of slots in alignment with said loops, and being folded upon itself for the passage of said loops through said slots.
- 10 2. A device of the character described comprising a curtain to be suspended on a rod, aligned loops secured to the curtain and arranged in rows, said curtain having near its top a series of slots in alignment with said loops, and being adapted to be folded upon itself for the passage of the loops through the slots, and adapted to be again folded upon itself to bring into contact the two uppermost rows of loops for engagement with the rod.
- 15 3. A device of the character described comprising a curtain to be suspended on a rod, aligned loops secured to the curtain and arranged in at

least three rows, said curtain having near its top a series of slots in alignment with said loops, and being adapted to be folded upon itself for the passage of the loops through the slots, and being adapted to be again folded upon itself whereby the rows of loops may be brought in contact for engagement with the rod by plaiting that portion of the curtain between the folds.

5 4. As a new article of manufacture, a curtain provided adjacent one end edge thereof with a transverse row of relatively spaced slots, and below said slots with relatively spaced rows of spaced loops aligning with the slots whereby the loops of a selected row may be passed through said slots when the curtain is folded at said one end, and the loops of the first selected row subsequently aligned with the loops of a second selected row of loops when the curtain is again folded upon itself to receive a rod trained through the aligned loops.
